VIBRATING DEVICE FOR DENTURE MATERIAL

Lazard L. Bailey, New Orleans, La.

Application October 22, 1952, Serial No. 316,214

4 Claims. (Cl. 259—72)

The present invention relates to improvements in vibrating device for denture material, and relates more particularly to the type embodying the vibratory principle for settling the investment or other material and removing the entrapped air therefrom.

An object of the present invention is to provide a device of the character described which is inexpensive in manufacture, has structural simplicity, and is highly portable taking up a minimum of laboratory space and which lends itself to being quickly set up and used.

Another object of the present invention is to provide a device having a constant or uniform rate of vibration as distinguished from intermittent or sporadic jarring whereby the investment or other material will be uniformly agitated and settled with removal of substantially all entrapped air.

A still further object of the present invention is to provide a device which will perform the above work and which is of extremely light weight.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a perspective view of a device constructed in accordance with the present invention;

Figure 2 is an exploded perspective view taken on an enlarged scale with parts broken away;

Figure 3 is a side elevational view taken on a still further enlarged scale on the line 3—3 of Figure 1; and

Figure 4 is a vertical cross sectional view taken on the line 4—4 in Figure 3.

Referring more particularly to the drawings, in which only one form of the invention is shown, 10 is an electric motor having a housing divided into two shells 11 and 12. The shell 11 has a substantially flat end wall 13 while the shell 12 has a dome-like end 14 having ventilation ports 15 therethrough.

An annular retaining ring 16 is secured to the motor casings or shells 11 and 12 and connects a handle 17 to the motor. The handle 17 has an axial bore 18 therethrough accommodating an electrical cord 19 for applying power to the motor 10.

The motor 10 has an armature shaft extension 20 upon which is secured an eccentric weight 21, semi-circular in shape. This eccentric weight 21 is secured to the armature shaft 20 by set screws 22 and 23.

On rotation, the eccentric weight 21 sets up vibrations and constitutes the vibrator element. Such element is preferably enclosed in a suitable casing, one preferable form of which is shown in the drawings to consist of a part-circular wall 24, open at its lower end as indicated at 29 (Figure 4). This enveloping wall 24 is open at its inner edge which is presented against the flat wall 13 of the motor housing. An upper segment of the wall 24, preferably opposite the bottom opening 29, is cut away as indi-

2

cated at 26 leaving edges 31 at opposite sides of the openings 26 and 29 which are in contact with the flat motor housing wall 13.

The outer side of the vibrator casing 24 is only partly closed by upper and lower outer walls 25 and 27 which are separated by a slot 30. The lower wall is preferably bulged outwardly and slotted as indicated at 33, one slot being shown in spaced relation to the upper free edge 34 and at opposite sides of a part-conic section 35 having its upper truncated apex lying substantially flush with the upper edge 34 and with its lower wider basal edge terminating at substantially the lower edge of the lower wall 27. The conic section is made by bulging outwardly the intermediate portion of the lower wall 27.

The upper wall 25 is provided with a hole 36 and holes 37 and 38 are made in the lower wall 27 at opposite sides of the conic section 35, thus the three openings 36, 37 and 38 are or may be in a triangulated arrangement to agree with similarly threaded holes 39 and 40 made in the flat end wall 13 of the motor housing.

Such openings are adapted to receive screws 32 or other fasteners by which the vibrator casing may be secured tightly against the flat wall 13 of the motor housing.

As shown more particularly in Figure 3, the screws may be adapted to pass through sleeves 28' and 28 which are arranged within the vibrator casing in registry with the holes 36, 37 and 38. Such sleeves 28 may be welded to the adjoining walls of the vibrator casing and provide extensive support for the fastenings 32. The uppermost sleeve 28' is axially shorter than the two lower sleeves 28 to conform to the cut-away portion 26 of the vibrator casing.

The vibrations are transmitted to an appropriate support, which, in the instance shown, consists of a plate 41. The plate is advantageously of plastic material and is secured to the motor housing in any appropriate manner, for instance at one point of anchorage by a screw or a bolt 42, the head of which may be set flush in the plate 41, the screw being threaded into the threaded wall or socket 43 in the motor housing, for instance in the upper portion of the shell 12 at a point remote from the vibrator.

The plate 41 extends outwardly and preferably beyond the dome 14 of the shell 12 and such plate is sufficiently wide to lie above all of the slots 15 to act as a shield to prevent investment material or other material from the vibrating operation from dropping down into the motor housing through such slots 15. The outer free edge of the plate is indicated at 41^a and such edge is preferably unsupported.

The opposite edge of the plate 41^b is preferably curved or rounded to the end that the plate is provided with an angularly disposed end portion 44 which depends from the plate in close proximity to the vibrator casing. Such dependent end portion 44 is provided with a hole 45 to receive the top screw or fastening 32, this screw passing through the plate portion 44, through the upper outer end wall 25 of the vibrator casing, through the sleeve 28' and thence into the threaded opening 39 in the flat wall 13 of the motor housing. This down-turned angled end portion 44 of the support plate 41 may lie in substantially the same plane as the lower wall 27. If desired, its lower free edge may be made to engage the upper edge 34 of the wall 27, although preferably such parts are slightly spaced apart. Also the inner surface of the angled end 44 may be forced by the top screw 32 against the upper wall 25, although preferably these parts are slightly spaced apart so as to give complete freedom of movement to the angled end 44. By adjusting the distance between the hole 45 and the screw anchorage 42, the angled end 44 may be made to keep its distance from any part of the vibrator casing even under the tightening action of the top screw 32. In this aspect the anchorage screw 42

3

serves as a stop to limit the movement of the angled end 44 toward the vibrator casing. A single screw 42 is preferably used to secure the support plate 41 to the motor housing and also a single screw 32 to secure the angled end 44 to the flat plate 13 of the motor housing.

The curved portion 41^b and the angled end 44 constitute a shield for preventing investment and other material employed in the vibrating operation from finding its way downwardly into the vibrator element.

The motor 10 is provided at a suitable point with a snap or other switch 46 for turning the motor on and off. This switch 46 is in a trigger-like relationship with respect to the handle 17, as best seen in Figure 1.

In operation the impression is boxed in and a mix of plaster or castone is made. Enough of this mix is then poured into the tray 47 (Figure 1) to cover the floor of the impression. The handle 17 of the device is placed in the palm of the hand of the user in such way that the handle 17 lies between the user's thumb and index finger in a pistol-like grip with the index finger engaging the snap switch 46. By moving this snap switch in one direction the motor is energized rotating the armature shaft 20 and the entrained eccentric weight 21. Such weight rotation gives rise to high frequency vibrations which are communicated to the plate 41 and to its angled end 44 in a manner presently described.

The tray 47 is held by its handle with the metal part of the tray resting on the plastic plate 41. The vibratory action is permitted to continue for a few seconds until the mixture is evenly spread over the impression and all air bubbles disappear; whereupon the switch 46 is turned off. The vibrator may be then laid on a bench or convenient support while more material is added to the impression, after which the vibrator is again lifted and put in operation to subject the attendant material to further vibratory treatment. If, after the second operation, more material is needed, it may be added and patted into position without any further vibration being necessary.

It will be noted that while the eccentric flywheel 21 has been illustrated as semi-circular, any geometric shape may be employed which will result in a non-balanced wheel. Varying degrees of off-balancing of the flywheel will result in settling the mix quickly or slowly and more evenly as desired.

This light weight portable vibrator requires no table space in the dental laboratory and may be employed to vibrate both large and small impressions. Because of the weight and surface area of the plate 41 and its angled end 44 the device is easy to keep clean.

The vibrations originate in the projected end 20 of the motor armature shaft, the outer end of which is free and unsupported. Due to its proximity to the source of vibration, the flat end wall 13 of the motor housing will acquire vibrations of similarly high frequency and intensity. Such vibrations are directly communicated through the top screw 32 to the angled end 44 of the support plate. In this way such angled end 44 receives vibrations of a high order of frequency and intensity which are transmitted to the curved end 41^b of the plate 41 and to this end of the plate 41.

On the other hand vibrations of a lower order of intensity are communicated to the support plate 41 at the anchorage point 42 due to the fact that this anchorage point is more remote from the source of vibration and because the vibrations tend to become somewhat damped because of passing through the armature shaft and bearings and other parts of the motor. It is found that the vibration intensity of the plate 41 in and about the anchorage point 42 is substantially less than the vibration intensity occurring at the curved portion 41^b. The arrangement, therefore, provides in a single support plate 41 areas of different vibration intensity where the tray 47 may be moved selectively in order to shake down and settle the material in the shortest space of time. Also different materials will respond more quickly to different

4

vibration intensities. The curved end 41^b of the plate is, due to this curvature, substantially unsupported. Due to the relative angular relation of the axes of the fastening 42 and top fastening 32, the angled end 44 of the plate is not interfered with in its vibratory movement by the screw 42. Moreover, the high intensity vibrations occurring in the angled end 44 tend to damp out as they approach the anchorage 42.

The openings 26, 29, 30 and 33 provide air circulation in and about the vibrator in the end of the motor. However, these openings and slots give to the vibrator casing a characteristic which enables the same to readily partake of the vibration of the end motor housing wall 13. The various slots and openings leave the walls more or less unsupported so that they can readily vibrate. The vibrations of the walls of the vibrator housing are, of course, communicated to the top screw 32 and to the angled end 44 to augment the vibrations communicated to this down-turned end 44 of the plate.

Although I have disclosed herein the best form of the invention known to me at this time, I reserve the right to all such modifications and changes as may come within the scope of the following claims.

What I claim is:

1. In a vibrating device, a motor driven vibrator, a vibratory part vibrated thereby, a support for material to be agitated and having an angled end, said support being mounted on the motor and having a connection between the vibratory part and said angled end for transmitting vibrations from said vibratory part to said support, said connections including a casing enclosing said vibrator, means including a sleeve in the casing contacting both said casing and a portion of said vibratory part.

2. In a vibrating device, a motor having an extension shaft, a vibrator on said shaft, a vibrating casing attached to said motor and surrounding said vibrator, said casing comprising a part-circular wall having an opening and an inner cut-away portion, and an outer side with upper and lower walls spaced apart, said lower wall having slots and an outwardly-bulged portion, and a plate for supporting material to be agitated having a portion in vibratory communication with said casing.

3. In a motor driven vibrating device for settling denture material and removing the entrapped air therefrom, a housing for said motor mounted for vibration having an end wall and a surrounding wall joined to the end wall and provided with a portion remote from the end wall, vibrating means for imparting vibrations to said housing comprising a shaft driven by said motor and a vibrator element on one end only of the shaft and operatively connected to said housing adjacent said end wall, whereby vibrations of a high order of frequency and intensity are imparted to the end wall and vibrations of less frequency and intensity are imparted to the remote portion of the surrounding wall, and a support having a substantially flat elongated portion for supporting the denture material and an angularly disposed end portion adjacent and operatively connected to said end wall so that vibrations of a high order of frequency and intensity are transmitted to the area of the flat portion of the support adjacent the angularly disposed end portion, the remote portion of the housing surrounding wall being adjacent and operatively connected to the flat portion of the support remote from the angularly disposed end portion so that vibrations of less frequency and intensity are imparted to the area of the flat portion of the support adjacent its connection to the remote surrounding wall portion, said areas of the support adapted to selectively support the denture material.

4. In a motor driven vibrating device for settling denture material and removing the entrapped air therefrom, a housing for said motor having an end wall and a surrounding wall provided with a portion remote from the end wall, vibrating means for imparting vibrations to said housing comprising a vibrator element connected to

70
75

said housing adjacent the end wall, whereby vibrations of a high order of frequency and intensity are imparted to the end wall and vibrations of less frequency and intensity are imparted to the remote portion of the surrounding wall, and a support for the denture material having a first part connected to the housing end wall and a second part connected to the remote portion of the housing surrounding wall so that an area of vibration of a high order of frequency and intensity is produced in said support adjacent the first part thereof and an area 10 of vibration of less frequency and intensity is produced in said support adjacent the second part thereof.
